Specification for Design.

Patented May 10, 1921.

Application filed October 23, 1920. Serial No. 419,097. Term of patent 14 years.

To all whom it may concern:

Be it known that I, WALTER A. BLACK, a citizen of the United States, and a resident of Perry, in the county of Dallas and State of Iowa, have invented a certain new, original, and ornamental Design for a Tire-Core, of which the following is a specification, reference being had to the accompanying drawing, forming part thereof.

Figure 1 is a side elevation of a portion of the tire core.

Fig. 2 is a top plan view of the same; and Fig. 3 is a sectional view, taken on the line 3—3 of Fig. 1.

I claim:

The ornamental design for a tire core, as shown.

Des Moines, Iowa, October 6, 1920.
